Original No. 2,783,568, dated March 5, 1957, Serial No.
541,401, October 19, 1955. Application for reissue
May 20, 1957, Serial No. 661,561

3 Claims. (Cl. 41—13)

Matter enclosed in heavy brackets [ ] appears in the
original patent but forms no part of this reissue specific-
cation; matter printed in italics indicates the additions
made by reissue.

This invention relates to an expanded ball decorative
element and to the method of using it in decorating.

An object of the invention is to provide a foliage article
to be decorated with a plurality of individual polystyrene
balls each of which is independently secured to the
article by means of an adhesive.

Another object of the invention is to teach a method
of inexpensively providing fire-resistant decorations for
articles to be decorated therewith.

A further object of the invention is to provide a foliage
article to be decorated with a plurality of expanded balls
which comprise expanded polystyrene.

Still another object of the invention is to provide a
decorative foliage article with expanded polystyrene balls
which are adhesively secured thereto for providing a
berry-like effect to the article.

These and other objects are attained by the means
described herein and as disclosed in the accompanying
drawings, in which:

Fig. 1 is a schematic view of a decorative foliage article
in the form of a sprig of evergreen in the process of being
provided with an adhesive coating.

Fig. 2 is a view of the foliage article of Fig. 1 after
being provided with the ornamental polystyrene balls in
accordance with the teachings of the present invention.

Fig. 3 is an enlarged sectional view of an individual
spike of the decorative foliage article of Fig. 2 showing
the manner in which an expanded polystyrene ball is
secured thereto.

Fig. 4 is a sectional view taken on line 4—4 of Fig. 3.

With reference now to Figs. 1 and 2 the numeral 10
denotes generally a decorative foliage article, which term
as used herein refers to and comprehends any and all
types of foliage, *branches and sprigs, with and without*
leaves, whether real or artificial, such as, by way of example
but not by way of restriction, evergreens, such as
holly, spruce, juniper, and other berry-bearing plants as
used by the floral trade.

In practicing the invention the foliage article to be
decorated is first provided with an air-dryable adhesive
which, in the preferred embodiment of the invention, may
be sprayed on for thereby providing a substantially
uniform coating of adhesive on the article.

A plurality of expanded polystyrene balls 20 substantially
spheroidally shaped are then placed on the adhesively
coated surfaces, while tacky, of the foliage article
whereby the overall pattern will be non-uniform, though
comprehensive throughout the adhesively coated area. As
best seen in Figs. 2 and 3, the balls 20 are lightly adhesively
adhered to the article and are randomly disposed in relatively
widely spaced relation lending a decorative appearance and
leaving a major portion of the foliage uncovered to serve as a decorative background

2

for the balls 20 which simulate berries. If desired, the
balls may be spaced close together leaving only a portion
of the foliage uncovered depending on the decorative
effect desired.

5 In Fig. 3 the numeral 12 denotes a branch and the
numeral 14 a spike or leaf projecting from the branch,
whereas the numeral 16 indicates the adhesive coating to
which balls 20 are secured. As best seen in this figure
a very small portion of the periphery of each of the balls
20 are adhesively secured to the foliage article permitting
a light adherence of the balls, with the remainder of the
periphery extending away from the foliage article.

The balls 20 comprise the expanded product obtained
when beads or granules of a polystyrene mixture contain-
ing a foaming agent, of which Freon and pentane
are examples, are subjected to a wet or a dry heat suffi-
cient to expand the granule into an expanded ball. The
degree of heat employed in the granule-expanding process
should be sufficient to raise the temperature thereof above
its critical temperature but below its melting tempera-
ture. By way of example, highly satisfactory results have
been obtained in those instances in which the granules
are placed in a steam cooker and heated from two to
four minutes under pressure approximating ten pounds
per square inch. As an alternate process heated air or
hot fluids such as ethyl glycol may be used to heat the
granules for producing the desired expansion. The re-
sultant expanded polystyrene balls may range in size from
1/8 to 3/4 of an inch in diameter and as best illustrated in
Fig. 4, each of the expanded balls comprises a central core
22 of cellular material which is surrounded by a cellular
shell 24 of greater density which is, in turn, completely
encased within a continuous polystyrene film 26.

20 The granules hereinabove referred to are commercially
available under the term "expandable polystyrene beads"
from chemical concerns such as, by way of example, Dow
Chemical Co.

25 The characteristics of the expanded polystyrene balls
are such that when they are subjected to open flame
they do not actively support combustion, but are dissi-
pated into the air, leaving no visible residue, thereby
making them ideally suited for decorative use.

30 If desired, the expanded polystyrene balls may be fur-
ther coated with a light coating of adhesive material after
they have been initially secured to the ornamental ob-
jects, in the manner illustrated in Fig. 3, said second ad-
hesive coating serving to more firmly anchor the expanded
polystyrene balls to the decorative objects; however, uni-
formly excellent results have been obtained, on a com-
mercial basis, in those instances wherein the second ad-
hesive coating was omitted.

35 After the expanded balls have been adhesively secured to
the supporting articles, the adhesive is preferably permitted
to set and dry, after which the article is shaken to dislodge
50 those of the balls which are not securely anchored to the
article.

40 If desired, the expanded polystyrene balls may be suit-
ably colored whereby to impart a varied effect to the final
product, however highly satisfactory results have been
55 obtained when using the expanded balls in their natural
form wherein their color is substantially white. A very
striking result is obtained when white expanded poly-
styrene balls are secured to ornamental objects such as
evergreens as illustrated in Fig. 2.

60 It should be understood that various changes may be
made, within the scope of the appended claims, without
departing from the spirit of the invention.

65 What is claimed is:

70 1. A plant product simulating a berry-bearing foliage
comprising a decorative foliage article, a layer of adhesive
coating the exterior surface of said article, a plurality of

substantially spheroidal polystyrene balls simulating berries lightly adhesively adhered to said article, said balls being disposed on said article so as to lend a decorative appearance thereto while leaving a portion of said article uncovered to serve as a decorative background for said balls, and with a very small portion of the periphery of each of said balls adhesively secured to said article permitting said balls to be lightly adhered and with the remainder of said periphery extending away from said article.

2. A plant product simulating a berry-bearing foliage comprising a decorative foliage article, a layer of adhesive coating the exterior surface of said article and a plurality of substantially spheroidal polystyrene balls simulating berries lightly adhesively adhered to said article and disposed at random thereon, said balls being disposed in relatively widely spaced relation on said article so as to lend a decorative appearance thereto while leaving a major portion of the foliage uncovered to serve as a decorative background for said balls, and with a very small portion of the periphery of each of said balls adhesively secured to said article permitting said balls to be lightly adhered and with the remainder of said periphery extending away from said article, and a second layer of adhesive coating the exposed exterior surface of said foliage and said balls to effect a final anchoring of the 25 balls to the article.

3. A product simulating a berry-bearing member comprising a decorative article, a layer of adhesive coating the exterior surface of said article, a plurality of substantially spheroidal polystyrene balls simulating berries lightly adhesively adhered to said article, said balls being disposed on said article so as to lend a decorative appearance thereto while leaving a portion of said article uncovered to serve as a decorative background for said balls, and with a very small portion of the periphery of each of said balls adhesively secured to said article permitting said balls to be lightly adhered and with the remainder of said periphery extending away from said article.
